United States Patent Office

Des. 219,104
Patented Nov. 3, 1970

219,104

EDITING CONSOLE

Jack R. Goodrich, Newark, Darrell S. Staley, Santa Clara,
and Robert W. Bornschlegel, Mountain View, Calif.,
assignors to Ampex Corporation, Redwood City, Calif.,
a corporation of California

Filed Mar. 24, 1969, Ser. No. 16,422

Term of patent 14 years

Int. Cl. D14—02

U.S. Cl. D26—5

The figure is a front, top and right side perspective view of an editing console showing my new design, the left side being a mirror image of the right side, and the bottom, rear and underside portions of the console being conventionally plain.

I claim:

The ornamental design for an editing console, substantially as shown and described.
